UNITED STATES PATENT OFFICE.

CHARLES KING, OF CHAFFEE, MISSOURI.

WICK FOR OIL STOVES.

Application filed July 21, 1921. Serial No. 486,437.

To all whom it may concern:

Be it known that CHARLES KING, a citizen of the United States, residing at Chaffee, in the county of Scott and State of Missouri, 5 has invented certain new and useful Improvements in Wicks for Oil Stoves, of which the following is a specification.

This invention relates to new and useful improvements in wicks for oil stoves, and 10 the primary object of the invention is to provide an improved device of this character which may be used for an indefinite period.

Usually wicks used in connection with oil stoves and the like are constantly burning 15 out so that new wicks are necessary, and the primary object of the invention, as stated above, is to provide a wick which will last for an indefinite period or for the life of the stove in which it is installed.

20 A further object of the invention resides in providing a wick formed of layers of fabric asbestos coated with putty or the like and having a layer of cotton interposed therebetween.

25 Still another object of the invention resides in providing a device which is simple and durable in construction, inexpensive to manufacture, and one which will be very efficient in use.

30 With these and other objects in view, my invention consists in the novel features of construction, combination and arrangement of parts as will be hereinafter referred to and more particularly pointed out in the 35 specification and claims.

In the accompanying drawing forming a part of this application—

Figure 1 is a side elevation of a device constructed in accordance with my invention, with parts broken away, and 40

Figure 2 is a detail vertical section therethrough.

In describing the invention I shall refer to the drawing in which similar reference 45 characters designate corresponding parts throughout the several views, and in which 1 designates a support of the usual or any preferred type for wicks of circular type used in oil stoves, said support carrying a wick 2 which will be described in detail herebelow.

50 My improved wick consists of two layers 3 and 4 of fabric asbestos, the inner opposed faces of which are coated with putty or the like, which in the drawing I have designated as 5. Interposed between the puttied faces

of the layers of asbestos is a layer of cotton 6, which constitutes the burning section of the wick. The provision of the layer of cotton between the layers of asbestos affords 60 substantially an air space for burning gas and when the wick is soaked in the oil this cotton layer will burn substantially as a gas and the puttied faces of the layers of asbestos will harden under the 65 heat and glaze the asbestos.

In the process of manufacture of this improved wick, I prefer to take two layers of asbestos of substantially equal size and coat 70 one face of each with puttied faces of similar material. The coated faces of the asbestos layers are brought together and a layer of cotton of the same size as the layers of asbestos is interposed therebetween. The complete wick is then placed through a roller to make 75 the elements adhere closely to one another and the device will be rolled in the formation desired. The air space will be provided between the layers of asbestos as described and the cotton is adapted to burn when the 80 complete wick is dipped in oil, the puttied faces of the asbestos hardening, as above described.

From the foregoing description it will be 85 seen that I have provided a simple, inexpensive and efficient means for carrying out the objects of the invention, and while I have particularly described the elements best adapted to perform the functions set forth, it is obvious that various changes in form, 90 proportion, and in the minor details of construction may be resorted to without departing from the spirit or sacrificing any of the principles of the invention.

Having thus described my invention, what 95 I claim is:

1. A wick of the class described comprising two layers of asbestos having their inner opposed faces coated with puttied faces and a layer of cotton interposed therebetween.

2. As an article of manufacture, a wick comprising two layers of asbestos, each having one face thereof coated with puttied faces, the puttied faces of said layers being brought together, a layer of cotton interposed between the coated faces of said layers to provide substantially an air space therebetween, and the layers of asbestos and cotton being rolled tightly together.

105 In testimony whereof I affix my signature. 110

CHARLES KING.
